UNITED STATES PATENT OFFICE.

DARIUS DAVISON, OF NEW YORK, N. Y.

FRONT WALL OF GAS-RETORT OVENS.

SPECIFICATION forming part of Letters Patent No. 240,672, dated April 26, 1881.

Application filed September 17, 1878.

To all whom it may concern:

Be it known that I, DARIUS DAVISON, of the city and State of New York, have invented new and useful Improvements in the Front 5 Walls of Gas-Retort Ovens; and I do hereby declare that the following is a full, clear, and exact description of the same, reference being had to the accompanying drawings, forming part of this specification.

10 A very great objection to the ordinary manner of constructing the front walls of gas-retorts is that the bolts which are employed for securing the iron mouth-pieces upon the clay retorts are inclosed in solid brick-work, which 15 becomes heated to a very high degree by the fire in the ovens. By such heat the bolts are expanded sufficiently to loosen the mouth-pieces from the retorts, thereby causing a serious leakage of gas between the two, and are 20 also very rapidly oxidized by the heat, and soon break off, disabling the retorts for further use, although they are otherwise good.

The object of my invention is to prevent the bolts from becoming heated sufficiently to produce the defects above mentioned.

25 To this end the invention consists in the combination, with a retort, a mouth-piece, and bolts securing the two together, of a front wall, supporting said retort, and constructed 30 with recesses or apertures in its outside, which receive within them or are in close proximity to the said bolts, whereby I provide for a slow circulation of comparatively cool air in immediate contact or in close proximity to said 35 bolts, and prevent their becoming too highly heated.

In the accompanying drawings, Figure 1 is a front view of a bench of retorts which are set according to my invention. Fig. 2 represents a vertical section upon the line A, Fig. 1; and Fig. 3 represents a horizontal section upon the line B, Fig. 1.

Similar letters of reference designate corresponding parts in all the figures.

45 D designates a number of retorts, the front

ends or mouths only of which are shown, and to them are secured ordinary cast-iron mouth-pieces by means of bolts F, in the usual way. E designates the front wall supporting the retorts, the front of which is represented as 50 about coincident with the ends or mouths of the retorts.

In order to more effectually retain the heat in the oven, and prevent great discomfort to the men working in front of the bench of retorts, I preferably construct this wall of three 55 or four or more widths of brick, as the nature of the case may require.

In order to prevent the bolts F from being so highly heated that their expansion would 60 loosen the iron mouth-piece of the retort and produce leakage between the mouth-piece and retort, and also to preserve the bolts and prevent their rapid oxidation, I construct the front wall, E, with recesses or apertures C in 65 close proximity to the bolts F, and which are open to the atmosphere, so that a slow circulation of comparatively cool air may take place in contact with the bolts, or in such close proximity thereto that they will be prevented 70 from being heated to an injurious degree.

By my invention I not only effect a saving of gas by preserving a tight joint between the mouth of the retort and the iron mouth-piece, but I preserve the durability of the bolts and 75 enable the retort so set to be used for a long time without repair.

What I claim as my invention, and desire to secure by Letters Patent, is—

The combination, with a retort, a mouth-piece, and bolts securing the two together, of a front wall supporting said retort and constructed with recesses or apertures in its outer side in close proximity to the said securing bolts, substantially as and for the purposes 85 herein set forth.

DARIUS DAVISON.
